UNITED STATES PATENT OFFICE.

ROBERT H. READ, OF WASHINGTON, DISTRICT OF COLUMBIA, ASSIGNOR TO GENERAL ELECTRIC COMPANY, A CORPORATION OF NEW YORK.

RESISTANCE-WIRE FOR ELECTRIC HEATERS.

1,192,457.

Specification of Letters Patent.

Patented July 25, 1916.

Original application filed July 19, 1910, Serial No. 572,778. Divided and this application filed May 28, 1914.
Serial No. 841,544.

To all whom it may concern:

Be it known that I, ROBERT H. READ, a citizen of the United States, residing at Washington, in the District of Columbia, 5 have invented new and useful Improvements in Resistance-Wires for Electric Heaters, of which the following is a specification.

This invention relates to fireproof insulated resistance wires or elements for electric heaters or the like and is applicable in 10 all cases where electrically generated heat is utilized or dissipated.

The heating wire is of a type comprising a high resistance core-wire inclosed in a 15 continuous metallic shell or armor and separated therefrom by a firmly packed annular layer or bed of mineral fireproof insulation in the form of powder. Such wires are alloys varying in specific resistance, but 20 always very high relatively to a good conductor such as copper, and are therefore adapted for heating work or such as requires a large diffusion or dissipation of energy, as contradistinguished from conducting work where a minimum dissipation 25 of energy is required for reasons of economical operation. With a mineral oxid insulation such as ground flint the temperature may be raised, as the substance has a 30 melting point above 2,000 centigrade and is not at all damaged by temperatures below its melting point. Ground flint, magnesia and many other oxids or compounds do 35 not become conductive when heated, the melting point being so high that they do not become a conductor of the second class (Nernst effect) except at very high temperatures. I may use any highly refractory insulating powder; I prefer, however, 40 to use ground flint, such as ground quartz or silex because of its cheapness and better thermal conductivity than other oxids or silicates, and which insures a quicker and more desirable operation for heater or rheostat work. Other mineral oxid powders 45 such as magnesia, alumina, emery, or sulfates, or carbonates such as chalk, or sili-

cates such as soapstone, clay or asbestos may be employed. The powder should be finely divided, free from granules to permit even 50 distribution and should pack well preventing the infiltration of air. I have had excellent results with a form of powder known on the market as silex, which is sold as a polisher of metals and is a pure form of 55 finely divided silica; a good quality of powder may be made by grinding flint finely and then separating the finer particles by levigation. Before using it should be heated strongly to expel all moisture. A finished 60 core-wire of high resistance alloy such as German silver, climax, or a nickel-chromium alloy is surrounded with the powder and telescoped within a seamless metal tube with a good clearance around the wire and 65 powder, and is then reduced in section. The armor may be of the same material as the core-wire or of a metal of the same expansion coefficient so as to avoid strains due to 70 differences in expansion under heat of the core and shell, or in some cases may be of copper or low brass or other metal that is difficultly fusible relative to one of low melting point, such as lead. I provide a terminal to guard the core-wire when 75 sharply flexed from contact with the jacket. This may be done by laying bare the core by removing a short piece of the jacket, using preferably a revolving knife such as a pipe cutter. A piece of copper wire may 80 be welded to the end of the core-wire, and a metallic tube filled with powdered flint or with cement pushed over the wire until it bears on the shell. It may be soldered or brazed to the shell, thus making a rigid 85 structure. The powder fills the tube and carries the heat away from the wire, and the copper will not get hot, and may therefore be led directly to a binding post or other circuit terminal. Thus I have an armored or sheathed heater wire in which 90 the shell offers a large surface of exposure to the air or other heat absorbing medium, permitting the passage of a greatly increased

current without overheating and maintaining the resistance core cool throughout its length.

This application is a division of my application #572,778 filed July 19, 1910 entitled Insulated conductors and process and apparatus for making the same.

In the accompanying drawings Figure 1 shows enlarged an armored wire powder-covered and surrounded by a seamless metallic jacket; Fig. 1^a is a cross-section of the same; Fig. 1^b shows the wire reduced until the jacket is firmly shrunk upon the filled or covered wire; Fig. 1^c shows the wire much reduced under the action of rolls or dies; Fig. 2 shows a step in the preparation of the heater wire; and Fig. 3 shows the terminal used at the ends of the heater wire.

A metal ribbon or tape 2 is passed to a curling die 3 which gradually forms it into a tube and at the open end is supplied previously heated dry insulating powder of the kind referred to, precautions being taken to provide a uniform supply of the powder as the tape is formed into a tube. A core-wire of high resistance alloy 4 is led axially of the tube being filled and at the same speed of travel. Means are provided for keeping the seam in a right line, as a blade of steel 8 at the front of the die. The seam may be brazed or welded, but good results may be obtained without this treatment as a seamless outer shell of the proper clearance effectually prevent leakage of the powder by closing tight on the folded tape, the seamless shell preventing any oozing of powder at the seam. The filled tube is slipped into a seamless metallic tube 5 previously drawn down to a size to permit it to be easily slid or telescoped into it. The structure thus provided is then drawn down in dies or otherwise reduced until the desired size is attained, when the powder will be hard packed and the core-wire central.

As will be seen in Fig. 1^a there is a good clearance between the seamless jacket and the powder covered wire core. In Fig. 1^b the jacket has been reduced and has been shrunk into intimate contact with the covered wire, while in Fig. 1^c the whole has been very much reduced in section. Such a wire may be reduced or drawn down to a very few thousandths inch in diameter.

I provide a terminal at the end of the core-wire so arranged as to provide effective radiation for the heat and to prevent metallic contact with the jacket. A simple and effective plan is to lay bare the core by removing a short piece of the jacket, using preferably a revolving knife such as a small pipe-cutter. A piece of copper wire 6 may be welded to the end of the core-wire and a metal tube having a porcelain bead 7 shrunk in the end and filled with powdered flint or cement as at 1 slipped over each end of

the shell thus making a rigid structure. The powder fills the tube and carries the heat away from the wire, and as the copper will not by reason of its low resistance get hot, it may be led directly to a binding post or other circuit terminal. If brazed seams are used the solder should have a sufficiently high melting point to permit annealing, or the seam should be welded or burned in an approved manner.

Having thus described my invention, what I claim as new and desire to secure by Letters-Patent is:—

1. A resistance wire for electric heaters or the like comprising a core of high resistance metal, a body of heat refractory insulation surrounding the core, and a metallic armor having the same coefficient of expansion as the core-wire inclosing the insulation.

2. An insulated resistance wire for electric heaters or the like comprising a core-wire of high resistance material, a closely packed refractory insulating powder surrounding the core-wire, and a metallic armor of similar expansion coefficient inclosing the powder.

3. The method of making a resistance wire for electric heaters or the like consisting in curling a sheet metal tape around a wire of high resistance, causing the tape to close into a long tube surrounding the wire, simultaneously feeding any insulating material into the space between the resistance wire and the tube, then inclosing the tube in a seamless metal jacket, and reducing the whole in cross-section.

4. A resistance wire for electric heaters comprising a high resistance core-wire surrounded with heat refractory powder insulation, a metal sheath around the core-wire, and insulating means for stopping the ends of the core-wire against leakage of powder.

5. A resistance wire for electric heaters comprising a high resistance core-wire surrounded with heat refractory insulation, a metallic sheath around the core-wire, and an insulating cement between the core-wire and the sheath at the ends of the element.

6. A resistance wire for electric heaters comprising a high resistance core-wire, a closely packed powder of heat refractory, insulating material from which the moisture has been expelled, and an integral metallic armor of a difficultly fusible metal tightly embracing the insulating material.

7. A resistance wire for electric heaters comprising a high resistance core-wire, a closely packed powder of heat refractory insulating material from which all moisture has been expelled, and a seamless metallic armor of a difficultly fusible metal on the outside holding the insulating material under compression.

8. A resistance wire for electric heaters comprising a high resistance core-wire,

closely packed powder of heat refractory
oxid insulating material from which all
moisture has been expelled, a seamless metal-
lic armor of difficultly fusible metal holding
the oxid under compression, and a fire-proof
cement at the ends of the wire.

9. The process of making an insulated
electric heating element, consisting in grad-
ually curling a sheet metal tape around a
10 resistance wire, causing the tape to close into

a long tube surrounding the wire, simul-
taneously feeding an insulating powder be-
tween the wire and tube, then inclosing the
tube in a tubular jacket and reducing the
whole in section until the powder is firmly 15
compacted on the wire.
